(57) **CLAIM**

The ornamental design for a multivariable trailer hitch assembly, as shown and described.

DESCRIPTION

FIG. 1 is a right-rear perspective view of a multivariable trailer hitch assembly showing my new design, wherein the keys shown in dash-dash line form no part of the claimed design;

FIG. 2 is a left-rear perspective view thereof, except further showing a further (hook) accessory in dot-dash line floating artificially in mid-air above the ball hitch, wherein the 'flat four' style trailer plug shown in dash-dash line (for illuminating the brake light forming the rear sidewall of step) forms no part of the claimed design;

FIG. 3 is a rear elevational view thereof;

FIG. 4 is a top plan view thereof;

FIG. 5 is a right side elevational view thereof;

FIG. 6 is a left side elevational view thereof;

FIG. 7 is a bottom plan view thereof;

FIG. 8 is a front elevational view thereof;

FIG. 9 is a partial sectional view taken along offset line IX-IX in FIG. 4;

FIG. 10 is a section view taken along line X-X in FIG. 5; FIG. 11 is a right-rear perspective view comparable to FIG. 1 except with the vertically-adjustable channel inverted and the hook replacing the ball, wherein the keys and 'flat four' style trailer plug shown in dash-dash line form no part of the claimed design;

FIG. 12 is a rear elevational view thereof;

FIG. 13 is a top plan view thereof;

FIG. 14 is a right side elevational view thereof;

FIG. 15 is a left side elevational view thereof;

FIG. 16 is a bottom plan view thereof; and,

FIG. 17 is a front elevational view thereof.
